APPARATUS FOR THE ELECTRICAL PROTECTION OF ELECTRIC DISCHARGE TUBE INSTALLATIONS

Harold Everard Monteagle Barlow,
London, EnglandApplication September 14, 1938, Serial No. 229,975
In Great Britain January 10, 1938

4 Claims. (Cl. 176--124)

This invention relates to the electrical protection of gaseous and other electric discharge tubes such, for example, as those used for electric signs, and electric lighting, and of electric 5 valve cathode ray, X-ray and other ray appliances, and it has for its object to provide a device which will automatically interrupt the current supply to the discharge tube upon variation or interruption of the current through the 10 discharge tube.

An electrical protective device according to the present invention broadly comprises an electro-magnetic relay in the discharge tube circuit, said relay being operable automatically to interrupt 15 the current supply to the discharge tube as a result of de-energisation upon variation or interruption of the current through the discharge tube.

In one embodiment of the invention in which 20 a transformer is employed for supplying the discharge tube the current input to the primary winding of the transformer is interrupted by the action of an electro-magnetic relay in the discharge tube circuit, said normally energised relay 25 operating automatically as a result of de-energisation upon variation or interruption of the current through the discharge tube.

The term "de-energisation" used in this specification is intended to mean both partial and 30 complete de-energisation.

In practice one or more relays or a composite 35 relay may be used and each such relay may be a differential relay having independently energised electro-magnets, the energisation of one 40 electro-magnet being effected by connecting its winding in the discharge tube circuit so that upon reduction or interruption of the current through the discharge tube said electro-magnet becomes de-energised and permits the armature of the 45 relay to move by attraction towards the other and energised electro-magnet, such movement being utilised to cause interruption of the current supply to the discharge tube.

A device according to the present invention 45 advantageously operates when either an open-circuit or an earth fault occurs on the electric discharge-tube circuit.

In an electric discharge-tube the applied potential required to set up the discharge is considerably greater than the potential required to maintain the discharge. Where transformer equipment with or without a choking coil is employed to supply such tubes it is so designed that the current in the secondary circuit remains approximately constant over a wide range of load-

ing, thus the voltage derived from the secondary of the transformer adjusts itself automatically to the impedance of the discharge-tube circuit to which the transformer is connected. Any leakage to earth on the secondary circuit tends to reduce the impedance of that circuit and so to cut down its terminal voltage. If the leakage is considerable the voltage applied to the tube will become insufficient to maintain the discharge, so that the current through it falls practically 10 to zero.

For example, my invention utilises for the purpose of earth fault protection of gaseous discharge-tubes the sudden extinction or considerable reduction of the electric discharge in the 15 tube when an overload, occurring in the secondary circuit of the transformer, is sufficient to reduce the voltage applied to the tube below the value required to produce or maintain ionisation. Open-circuit protection is also achieved in my 20 invention by the accompanying interruption of the current through the discharge-tube.

Thus when the middle point of the secondary winding of the transformer is earthed a convenient arrangement is to employ two differential 25 electromagnetic relays. One of these relays operates with an earth fault or open-circuit on one side of the earth point of the secondary circuit and the second relay operates when similar conditions prevail on the other side of the earth 30 point. The movement of the armature of either relay actuates a switch or fuse to interrupt the primary current of the transformer.

In order that the invention may be clearly understood and carried into effect one embodiment 35 of the same, showing the use of a transformer with two differential relays, will now be described by aid of the accompanying diagram.

With reference to the accompanying drawing of a single-phase transformer, each of the relays 40 employed in this case have two distinct electro-magnets U and W supplied with currents derived respectively directly or through condensers from the secondary winding S and either an additional winding X with which is linked the primary flux, 45 or from an additional winding with which part of the primary flux only is linked, or from parallel or series connection with the primary winding P itself. The armatures C₁ and C₂ are quite independent. Each is hinged at one end and free 50 to move into contact with the poles of either one or other of their associated electromagnets. Under ordinary operating conditions the armature C₁ is held in contact with the poles of electromagnet U₁ and the armature C₂ in contact 55

with the poles of electromagnet U_2 the armatures remaining thus when the alternating current supply to the terminals T is disconnected.

If an earth fault occurs on the left-hand side 5 of the earth point E of the high voltage circuit the left-hand half of the secondary winding becomes more heavily loaded due to the formation of the parallel circuit to earth. This causes a reduction of the terminal voltage of the secondary 10 winding as a whole and if the change is sufficient, ionisation in the discharge-tube N will cease and the current through it will fall almost to zero. In such circumstances the right-hand half of the secondary winding and with it the winding on the 15 electromagnet U_2 will carry no current. The electromagnet W_2 remains energised so that the armature C_2 is pulled over into contact with the poles of W_2 and in so doing opens the small mercury switch D by rocking it about the spindle 20 H when the arm G_2 strikes the projection F . At the same time the left-hand half of the secondary winding and with it the winding on the electromagnet U_1 carries the earth leakage current and this will usually be sufficient to retain the armature C_1 in contact with the poles of the electromagnet U_1 but it is immaterial whether or not this armature is released at the same time.

If an earth fault occurs on the right-hand side of the earth point of the high voltage circuit 30 the process is repeated with an interchange of the operation of the relays.

In the case of an open-circuit or interruption of the secondary circuit the currents through the windings of both electromagnets U_1 and U_2 are 35 reduced to zero, whilst electromagnets W_1 and W_2 remain energised. The armatures C_1 and C_2 are pulled over into contact with the poles of W_1 and W_2 respectively, both operating to open the mercury switch D .

40 Since the mercury switch is connected by means of flexible leads L in series with the primary of the transformer, the supply is automatically interrupted under both earth fault and open-circuit conditions on the secondary.

45 The armatures C_1 and C_2 remain in the "off" positions until replaced in the ordinary working positions.

In practice it may be convenient to construct the apparatus so that one differential relay is 50 placed vertically above the other, the two armatures being hinged about the same vertical spindle. The electromagnets W_1 and W_2 can then be combined into a single unit operating jointly on the two armatures.

55 In cases where the secondary winding of the transformer is earthed at one end a single differential relay with the accompanying switch is sufficient.

60 A single differential relay may also be employed when the earth potential point of the circuit through the discharge-tubes is accessible, such, for example, when several discharge tubes are connected in series so that the winding U of the relay can be connected in series at that point.

65 Alternatively the earth potential point may suitably be derived by forming such a subsidiary discharge-tube circuit in parallel with the main discharge-tube circuit and the winding U of the differential relay connected in series with this parallel circuit at the earth point. These arrangements would apply when the current through the discharge-tube is derived either from a transformer equipment or from any other source A. C. or D. C. interrupted or otherwise,

75 the electromagnet W being energised in parallel with the supply.

In all cases the winding U of the differential relay must be connected at an earth potential point in series with the discharge-tube circuit, 5 either the main one or a subsidiary one in parallel.

Instead of using the rocking type of mercury switch in the primary circuit of the transformer, a magnetic type may be employed in which the armature of each pair of electromagnets itself 10 bridges the two mercury contacts or operates such a bridge.

Another method is to employ the armatures of the relays to short-circuit the primary supply mains and blow fuses connected in the circuit or 15 alternatively to make the armatures cause a mechanical breakage of such fuses.

What I claim is:

1. An electrical protective device for gaseous electric discharge tubes comprising in combination two electromagnets which are normally energised by current from the discharge tube circuit one of said electromagnets becoming de-energised when an earth fault occurs in said circuit and the other electromagnet being de-energised when an open circuit occurs in said discharge tube circuit, an armature associated with each said electromagnet, and current interrupting means operatively associated with said armature the arrangement being such that de-energisation of either electromagnet releases its associated armature for movement to effect operation of the current interrupting means to cut off the current supply to the discharge tube circuit. 30

2. An electrical protective device for gaseous electric discharge tubes comprising in combination four electromagnets arranged in pairs to form two differential relays one electromagnet in each pair being permanently connected in the 40 discharge tube circuit, an armature associated with each pair of electromagnets, a separate circuit for permanently energising the other electromagnet in each pair, and current interrupting means operatively associated with each said armature, the arrangement being such that said first mentioned electromagnets are alternatively de-energised upon variation or interruption of the current through the discharge tube, the de-energisation of one said electromagnet taking 50 place as a result of an open circuit and the other as a result of an earth fault, whilst the other and opposing permanently energised electromagnet operates to attract the armature of the de-energised electromagnet and effect operation of the 55 current interrupting means to cut off the current supply to the discharge tube circuit.

3. An electrical protective device for gaseous electric discharge tubes comprising in combination, a static transformer supplying the discharge 60 tubes four electromagnets arranged in pairs to form two differential relays one electromagnet in each pair being permanently connected in series with the secondary winding of the transformer, an armature associated with each pair of electromagnets, an additional winding on the transformer core linked with the primary flux of the transformer for permanently energising the other electromagnet in each pair, and current interrupting means operatively associated with 65 each said armature, the arrangement being such that said first mentioned electromagnets are alternatively de-energised upon variation or interruption of the current through the discharge tube, the de-energisation of one said electro- 75

magnet taking place as a result of an open circuit and the other as a result of an earth fault, whilst the other and opposing permanently energised electromagnet operates to attract the armature of the de-energised electromagnet and effect operation of the current interrupting means to cut off the current supply to the discharge tube circuit.

4. An electrical protective device for electric discharge tubes comprising in combination, a static transformer supplying the discharge tube, means for interrupting the current input to the primary winding of the transformer, two electromagnets in series with the secondary winding of

the transformer, so as normally to be energised when current flows to the discharge tube, a pivoted armature associated with each electromagnet to form a relay said armature being operatively associated with the current interrupting means in such manner that upon variation or interruption of the current through the discharge-tube the one or other of the electromagnets becomes de-energised to permit movement of its armature to effect operation of the current interrupting means to break the supply to the primary winding of the transformer. 5

HAROLD EVERARD
MONTEAGLE BARLOW.
